(21) Appl. No.: **29/620,157**

The ornamental design for container for heating and cooling foods and beverages, as shown and described.

DESCRIPTION

(22) Filed: **Jul. 26, 2016**

FIG. 1 is a front and rear elevation view of the container for heating and cooling foods and beverages of our design assembled.

(51) LOC (10) Cl. **07-07**

FIG. 2 is a right and left side elevation view thereof.

(52) U.S. Cl.

FIG. 3 is a front exploded view thereof showing a closure, inner container and an outer container.

USPC **D7/608; D7/629**

FIG. 4 is a left side exploded view thereof showing a closure, inner container and an outer container.

(58) **Field of Classification Search**

FIG. 5 is a rear exploded view thereof showing a closure, inner container and an outer container.

USPC D7/605-608, 602, 629, 538-542, 391,

11/20

D7/392, 392.1

FIG. 6 is a left side exploded view thereof showing a closure, inner container and an outer container.

CPC B65D 43/0218; B65D 45/20; B29C

45/0025; A45C 5/04; A45C 11/16; A45C

45/0025; A45C 5/04; A45C 11/16; A45C

11/20

See application file for complete search history.

FIG. 7 is a top plan view of the closure.

(56)
